UNITED STATES PATENT OFFICE

2,531,094

DUAL POWER UNIT FOR DUPLEX PUMP

Russell R. Waterman, Lodi, Calif.

Application July 2, 1946; Serial No. 681,000

5 Claims. (Cl. 121—114)

1

This invention is directed to, and it is an object to provide, an improved steam driven water pump of the duplex type.

Another object of the invention is to provide a crank unit in novel assembly with the two-power cylinders of the pump, whereby positive and correctly timed motion of the pistons of said power cylinders is accomplished. The operation of the pump is thus smooth and effective, and the usual timing springs are eliminated in their entirety.

A further object of the invention is to provide a duplex pump which is practical, rugged, and yet simple in its construction; the pump being designed so that it requires a minimum of maintenance and repair.

These objects are accomplished by means of such structure and relative arrangement of parts as will fully appear by a perusal of the following specification and claims.

In the drawings:

Fig. 1 is a longitudinal elevation of the pump, mainly in section.

Fig. 2 is a plan view, with the power cylinder unit in section.

Fig. 3 is a cross section on line 3—3 of Fig. 2.

Fig. 4 is an end view of the crank, detached.

Fig. 5 is a diagrammatic plan view of the power cylinder unit, including the porting and conduit arrangement.

Referring now more particularly to the characters of reference on the drawings, the improved duplex pump comprises a main frame, indicated generally at 1, which main frame includes a bed 2, upstanding end heads 3 and 4, and a central vertical web 5 connecting the end heads 3 and 4 above the bed 2.

The main frame 1 is supported, from below, by a pedestal in the form of a hollow crankcase 6, which crankcase includes a drain plug 7 adjacent the bottom thereof.

A dual pump unit, indicated generally at 8, is mounted in connection with and projects outwardly from the end head 3, while a dual-power cylinder unit, indicated generally at 9, is mounted in connection with and projects outwardly from the end head 4.

The power cylinder unit 9 includes therein a pair of cylinders 10 and 11 disposed in parallel side by side relation and having pistons 12 and 13, respectively, mounted for reciprocation therein. The pistons 12 and 13 are each connected to a pump rod; the pump rods being indicated at 14. The pump rods extend through the end head 4 in packing glands 15, thence extend lengthwise over the bed 2, and pass through packing glands 16 on the end head 3. Within the pump unit 8 the latter includes a pair of pumping assemblies, one of which is shown in section in Fig. 1. Each pumping assembly includes a double acting pump plunger 17 connected to the corresponding pump rod 14, and running in a pump barrel 18. Each pump assembly also in-

2

cludes an intake passage 19, intake valves 20, outlet valves 21, and an outlet passage 22. The intake passages 19 of the separate pump assembly are in communication, as are the outlet passages 22 of said assemblies, whereby the pump unit 8 includes only a single intake port (not shown), and a single outlet port 23.

Steam is supplied to the dual power cylinders through bores 24 in the pump rods 14, said bores opening to the adjacent ends of said pump rods and having steam fed thereinto from a steam delivery manifold 25 on the outer end of the power cylinder unit 9; said manifold being arranged so that the pump rods may reciprocate therein while having a constant supply of steam fed thereto. Steam is delivered to the manifold 25 through a fitting 26. The steam system of the dual power cylinder unit 9 will hereinafter be described in detail, and for the present it suffices to note that the pistons 13 are fixed on the pump rods 14 to run with one piston exactly one-half stroke behind the other piston; the stroke of both of said pistons being relatively short. This relationship of the pistons to each other is positively and exactly maintained through the medium of a crank unit which is constructed as follows:

A pair of transversely spaced, longitudinal guide rods 27 are mounted in the crankcase 6 adjacent but short of the top thereof and in parallel relation to each other, as well as to the pump rods 14. Each guide rod 27 is disposed in vertical alignment with the corresponding pump rod 14.

Reciprocable guide sleeves 28 are disposed on the rods 27, and each sleeve includes a depending guideway 29 in which a vertically movable slide block 30 is mounted. A crankshaft, indicated at 31, is disposed transversely in the crankcase 6 and is supported, at opposite ends, by bearing caps 32 fixed in connection with opposite sidewalls of said crankcase. The crankshaft 31 includes a pair of cranks 33 disposed in vertical alignment with corresponding guide rods 27, and said cranks 33 carry the slide blocks 30. A counterbalancing crank 34 is included in the crankshaft 31 between the cranks 33. The cranks 33 are disposed, or rotate, 90° apart.

Each guide rod 27 includes, centrally of its ends, an upstanding boss 35 which extends upwardly through an elongated opening 36 formed in the bed 2 and surrounded by an upstanding flange 37. Each boss 35 projects above the corresponding flange 37 and includes a bore 38 through which the corresponding pump rod 14 extends. Each boss 35 is fixed to the corresponding pump rod 14 by a set screw 39. A protective cap 40 is carried on the upper end of each boss 35 and depends in clearance but encompassing relation to the adjacent flange 37, whereby to prevent access of foreign matter through the elongated openings 36 to the crankcase.

By reason of the above described crank unit the pistons 13 are positively and accurately main-

tained in proper timed relation to each other, and additionally the reversal of each piston at the end of its stroke, and at the beginning of the next stroke, is power assisted from the other piston which is then being steam actuated.

The steam system for the dual power cylinder 9 comprises the following:

Each piston 13 is double acting and formed with a pair of spaced apart, annular, steam feeding grooves 41 adjacent but short of the ends of such piston, and a relatively wide, annular, steam exhausting groove 42 centrally of said ends and between the grooves 41. Each piston has a radial passage 43 opening between each stem feeding groove 41 and the bore 24 in the corresponding rod 14.

The wall of each cylinder 11 is formed with a pair of ports 44 in longitudinally spaced apart relation; the spacing of ports 44 being lesser than that of the corresponding steam feeding grooves 41.

Two pairs of steam ducts 45 are formed in the cylinder unit 9 and each pair connects between opposite ends of one cylinder 11 and the opposite ports 44 of the other cylinder; each cylinder wall having a relatively wide exhaust port 46 therethrough centrally between the ports 44. An exhaust duct 47 connects between the exhaust port 46 of one cylinder and a corresponding port 48 in the wall of the other cylinder; the latter having its exhaust port 46 open to atmosphere.

By reason of the above described porting and duct arrangement, it will be evident that each piston 13 controls the steam delivery to and exhaust from the other cylinder; each piston being under steam pressure at one end and exhausting at the other end only intermediate the ends of its stroke. At the end of each stroke and at the outset of the next and reverse stroke, each piston derives its movement from the other piston—which is then being steam driven intermediate the ends of a stroke—through the medium of the crank unit which connects the pump rods 14. The crank unit thus serves to positively and accurately maintain the piston in time, and to reverse the motion of each piston at the end of each stroke, which assures of smooth, constant, and reliable operation. The 90° apart relationship of the cranks 33, and the relation thereof to the connected parts, positions each crank for a power application thereto when the corresponding piston 13 is steam driven.

A pocket 49 on the top of each slide block 30 traps oil from the case 6 and at the top of the stroke of said block the pocket forces the trapped oil through an opening 50 in the corresponding sleeve 28 whereby to lubricate the latter. Excess oil escapes from the sleeve through outlet holes 51 in the sides of the sleeve.

From the foregoing description it will be readily seen that there has been produced such a device as substantially fulfills the objects of the invention, as set forth herein.

While this specification sets forth in detail the present and preferred construction of the device, still in practice such deviations therefrom may be resorted to as do not form a departure from the spirit of the invention, as defined by the appended claims.

Having thus described the invention, the following is claimed as new and useful, and upon which Letters Patent are desired:

1. In a motor which includes a pair of parallel fluid pressure operated pistons provided with

piston rods; a crankshaft journaled at a right angle to and adjacent the piston rods, a pair of cranks fixed to the crankshaft, a lineal-rotary motion translating means connected between each piston rod and one of the cranks, such means comprising a guide rod fixed parallel with respect to the piston rod and disposed between such piston rod and the crank, a guide sleeve movable along the guide rod, means fixing the sleeve to the piston rod, a vertically disposed guideway fixed to the sleeve at right angles thereto, and a guide block journaled on the crank and being slidable in the guideway.

2. A motor as in claim 1 in which the means fixing the sleeve to the piston rod comprises a boss on the sleeve provided with an opening through which the piston rod extends, and a set screw mounted through the boss and engaging the piston rod.

3. In a motor comprising a main frame which includes a bed, a pair of parallel cylinders supported on the frame, fluid pressure operated pistons disposed in the cylinders and provided with piston rods disposed above the bed; a crank case formed with the frame below the bed, the bed being provided with an opening into said crank case adjacent each piston rod, a crank shaft journaled in said crankcase, a pair of cranks fixed to the crank shaft, a lineal-rotary motion translating means connected between each piston rod and one of the cranks, such means including a vertically guided block journaled on the crank, and means mounting said block in connection with the piston rod, such means extending in part through said opening.

4. In a motor comprising a main frame which includes a bed, a pair of parallel cylinders supported on the frame, fluid pressure operated pistons disposed in the cylinders and provided with piston rods disposed above the bed; a crank case formed with the frame below the bed, the bed being provided with an opening into said crankcase adjacent each piston rod, a crank shaft journaled in said crank case, a pair of cranks fixed to the crank shaft, a lineal-rotary motion translating means connected between each piston rod and one of the cranks, such means comprising a guide rod mounted within the case in parallelism with the piston rod, a guide sleeve movable along the guide rod, a vertically disposed guideway fixed to the sleeve at right angles thereto, a guide block journaled on the crank and slidable in the guide way, and a boss on the sleeve projecting upwardly through the adjacent opening in the bed and being connected with the piston rod.

5. A motor as in claim 4, including an upwardly extending flange formed about each opening, and a skirted cap fixed to each boss and overhanging the adjacent flange whereby to prevent access of foreign material through the openings.

RUSSELL R. WATERMAN.
